UNITED STATES PATENT OFFICE.

DANIEL SALAZAR M., OF MEDELLIN, COLOMBIA.

SYSTEM OF DISTRIBUTING ELECTRICITY AND APPARATUS THEREFOR.

Application filed March 7, 1922. Serial No. 541,875.

To all whom it may concern:

Be it known that I, DANIEL SALAZAR, a citizen of Colombia, South America, residing at Medellin, Colombia, South America, have invented a certain new and useful Improvement in Systems of Distributing Electricity and Apparatus Therefor, of which the following is a full, clear, and exact description.

- 10 My invention relates to improvements in systems of distributing electricity and apparatus therefor, and has for its object to produce a system in which groups of translating devices are controlled from a single point through a succession of switching means, each group having a controlling switch which cuts in and out the translating devices of said group and also controls the next succeeding switch.
- 15 It further has for its object to provide such a system in which all of a plurality of successively acting switching devices are controlled by a single time operated switch.

20 It further has for its object to provide a special switch for use in said system.

25 A further object of my invention is to provide a combined house lighting and street lighting system in which a plurality of groups of street lights or other translating devices are controlled by a series of inter-related switches which cut in and out of circuit by the opening and closing of the first switch of the series.

30 A further object of my invention is to provide an alternating current system in which the above objects are obtained.

35 The following is a description of an embodiment of my invention reference being had to the accompanying drawings, in which,—

40 Figure 1 shows a plan view of the preferred form of switch;

45 Fig. 2 shows a section of the same on the line 2—2 of Fig. 1;

50 Fig. 3 shows a diagram of my improved system the individual groups being connected in circuit, and

55 Fig. 4 shows the position of the first switch when the groups are cut out of circuit.

Referring more particularly to the drawings Fig. 1 shows a switch having a base 2 upon which are mounted circuit terminals 4, 6 and 8 which are respectively connected

60 to switch contacts 10, 12 and 14 as shown

diagrammatically in Fig. 3. Upon this base are also mounted circuit terminals 16, 18 and 20 which are respectively connected to switch contacts 22, 24 and 26 as shown in Fig. 3. 28 is a switch arm carried by a bar 30 pivoted at 32. This switch arm is always electrically connected to terminal 4 and is adapted to electrically connect either the contacts 10 and 12 or the contacts 12 and 14. 34 is another switch arm mounted upon a bar 36 pivoted at 38 and adapted to make electrical connection between either the contacts 22 and 24 or 24 and 26. The bars 32 and 36 are connected by toggle levers 40 and 42 to a sleeve 44 carried by a magnetic core 46. The ends of this magnetic core are surrounded by solenoids 48 and 50 mounted upon the base 2. The solenoid 50 is electrically connected between the terminal 4 and contact 10 and the solenoid 48 is electrically connected between the terminal 8 and contact 14. When the solenoid 50 is energized the parts are moved to the position shown in Figs. 1 and 3. When the solenoid 48 is energized the core 46 is moved in the other direction to the position shown in Fig. 4 so that the switch arms 28 and 34 electrically connect the switch contacts 12 and 10 and the switch contacts 24 and 26 respectively for the purposes hereinafter referred to.

Referring to Figs. 3 and 4, 100 is an alternating current generator to the supply mains of which transformers 102, 104, 106 and 108 are connected in multiple. The secondaries of the transformers 104, 106 and 108 supply work circuits containing translating devices 104', 106' and 108' respectively, which may be considered to be house lights or the like. Because of the multiple arc arrangement of the system these secondary work circuits are independent of one another. The secondary of the transformer 102 is connected to the terminal 6 of the first switch and to a revolvable contact member 110 operated by a suitable time clock 112. This contact member 110 is adapted to engage and disengage contacts 114 and 116 which are respectively connected to the terminals 8 and 4 of the first switch. The terminal 20 of each preceding switch is connected to the terminal 8 of a succeeding switch and the terminal 18 of each switch is connected to one of its respective branch mains at 118. The terminal 16 of each suc-

ceeding switch is connected to one main of the corresponding group work circuits 104², 106² and 108² whose other main is connected to the second main of a branch circuit at any desired point thereof, for instance 120. The terminal 4 of each succeeding switch is connected to the same main of the group as the terminal 16 of the preceding switch and at any desired point. In carrying out my invention this connection is usually made at a point beyond some or all of the translating devices in the group circuit, such for instance as at the point 122.

With this arrangement the operation is as follows:

The alternating current generator 100 generates a relatively high potential current which is transformed by the transformers 104, 106 and 108 and delivered to the translating devices 104', 106' and 108' in the manner ordinarily employed in the well known multiple arc alternating current system. The transformer 102 supplies energy by its secondary circuit which is controlled by the time actuated contact 110. As will be seen this secondary circuit is normally open.

With the parts in the position shown in Fig. 3 the member 110 moves clockwise. The contact 114 is supposed to be engaged by the contact 110 at a definite hour, such as six o'clock a. m. The contact 116 is supposed to be reached at a definite hour, such as eight o'clock p. m. the member 110 revolving once in twenty four hours. The positions of the contacts 114 and 116 may be made such that they will correspond to any desired hours. When the switch arm 110 reaches the contact 114 it closes a circuit through a secondary of the transformer 102, the switch arm 28 and the solenoid 48. This causes the core 46 to move so as to cause the switch arm 34 to break its engagement with the contact 22 and make engagement with the contact 26 which cuts the group 104² out of circuit. It also moves the switch arm 28 out of engagement with the contact 14 and into engagement with the contact 10 so that when the contact arm 110 reaches the contact 116 a current will be passed through the solenoid 50 of the first switch restoring the parts to the position shown in Fig. 3.

The engagement of the switch arm 34 of the first switch with its contact 26 establishes a circuit through the solenoid 48 of the second switch causing that switch to operate in the same manner in which the first switch operated and to produce the same results with regard to its group 106² and its succeeding switch. The third switch when operated by the second switch will produce the same effect upon its group 108² and upon any similar subsequent switch.

It is to be noted that whenever a switch

actuating current is closed it actuates a switch and is immediately opened by that switch so that normally all of the actuating circuits are open, being momentarily closed for actuating purposes. It is further to be noted that inasmuch as the terminals 6 and 18 of adjacent switches can be connected to the branch mains supplying the same house lights at any desired point and inasmuch as the contacts 4 of all except the first switch can be connected at any desired point to the main of the proper group, the second and all subsequent switches can be located at a considerable distance from the first switch and from each other, the branch and group mains carrying lighting current being used to establish the inter-switch connections with the exception of the single connection between terminals 20 and 8 of adjacent switches. It is therefore necessary to have but one controlling connection which is of any considerable length and as above stated this controlling connection is normally out of circuit and when in circuit carries current only momentarily.

The position shown in Fig. 4 corresponds to that when the group translating devices are out of circuit.

By using this arrangement in which the lighting circuits are used for the most part to establish controlling circuits for successive switches and in which the extended connection between two succeeding switches derives its current from the work circuit supplying the group controlled by the preceding switch there are no controlling circuits of higher potential than the working potential and there are no controlling magnets or solenoids which are in series so as to introduce resistance or inductance which will interfere with the action of any other solenoid or magnet. The system therefore, overcomes many of the defects of systems which have heretofore been in use presenting a multiple arc system for street lighting with a simple and effective control and eliminating a special series controlling circuit, and any special switch controlling circuit in which current is normally passing for any considerable period.

What I claim is:

1. In a system of electrical distribution, a plurality of remote control switches arranged in succession, an independent work circuit for each switch and translating devices thereon, each preceding remote control switch controlling a succeeding remote control switch and cutting in and out translating devices from its own work circuit each succeeding remote controlled switch being controlled through the independent work circuit of the preceding switch.

2. In a system of electrical distribution, a plurality of remote control switches arranged in succession, an independent work cir-

cuit for each switch and translating devices thereon, each preceding switch controlling a succeeding switch and cutting in and out translating devices from its own independent work circuit, each succeeding remote controlled switch being controlled through the independent work circuit of the preceding switch, and a time switch for opening and closing the first of said remote control switches.

3. In a system of electrical distribution, the combination of a source of alternating current, transformers connected thereto in multiple, independent secondary work circuits supplied by said transformers, translating devices for said work circuits, remote control switches for each of said work circuits controlling said translating devices and constituting a succession of switches, each preceding switch controlling a succeeding switch through energy supplied by the secondary work circuit of the preceding switch.

4. In a system of electrical distribution, the combination of a plurality of independent work circuits, a translating device for each independent work circuit, a remote control switch for cutting in and out the said translating device of each independent work circuit, said remote control switches having opening and closing control circuits and constituting a succession of switches each preceding remote control switch controlling the control circuits of a succeeding remote control switch, so as to cause the movements of each succeeding switch to be similar to the movements of the preceding switch, means for alternately energizing the opening and closing control circuits of the first remote control switch, and means for locally breaking the energized control circuit of each remote control switch and locally closing the other on each of the movements of said remote control switches, each succeeding remote controlled switch being controlled through the independent work circuit of the preceding switch.

5. In a system of electrical distribution, the combination of a plurality of independent work circuits, a translating device for each independent work circuit, a remote control switch for cutting in and out the said translating device of each independent work circuit, said remote control switches having opening and closing control circuits and constituting a succession of switches each preceding remote control switch controlling the control circuits of a succeeding remote control switch, so as to cause the movements of each succeeding switch to be similar to the movements of the preceding switch, each succeeding remote controlled switch being controlled through the independent work circuit of the preceding switch, means for alternately energizing the opening and closing control circuits of the first remote

trol switch, and other translating devices connected with said work circuits independently of said remote control switches.

6. In a system of electrical distribution, the combination of a plurality of independent work circuits, a translating device for each independent work circuit, a remote control switch for cutting in and out the said translating device of each independent work circuit, said remote control switches having opening and closing control circuits and constituting a succession of switches, each preceding remote control switch controlling the control circuits of a succeeding remote control switch, so as to cause the movements of each succeeding switch to be similar to the movements of the preceding switch, each succeeding remote controlled switch being controlled through the independent work circuit of the preceding switch, means for alternately energizing the opening and closing control circuits of the first remote control switch, and transformers in multiple supplying energy to said work circuits respectively.

7. In a system of electrical distribution, the combination of a plurality of independent work circuits, a translating device for each independent work circuit, a remote control switch for cutting in and out the said translating device of each independent work circuit, said remote control switches having opening and closing control switches and constituting a succession of switches, each preceding remote control switch controlling the control circuits of a succeeding remote control switch so as to cause the movements of each succeeding switch to be similar to the movements of the preceding switch, each succeeding remote controlled switch being controlled through the independent work circuit of the preceding switch, and a time switch for closing the control circuits of the first remote control switch alternately.

8. In a system of electrical distribution, the combination of a plurality of independent work circuits, a translating device for each independent work circuit, a remote control switch for cutting in and out the said translating device of each independent work circuit, said remote control switches having opening and closing control circuits and constituting a succession of switches each preceding remote control switch controlling the control circuits of a succeeding remote control switch, so as to cause the movements of succeeding switches to be similar to the movements of the preceding switches, means for alternately energizing the opening and closing control circuits of the first remote control switch, each succeeding remote controlled switch being controlled through the independent work circuit of the preceding switch, and means for locally breaking the energized control switches of each remote

control switch and locally closing the other on each of the movements of said remote control switches, said control circuits of succeeding switches being connected to and disconnected from said work circuits respectively by the next preceding switch.

9. In a system of electrical distribution, the combination of a plurality of independent work circuits, a translating device for each independent work circuit, a remote control switch for cutting in and out the said translating device of each independent work circuit, said remote control switches having opening and closing control circuits and constituting a succession of switches each preceding remote control switch controlling the control circuits of a succeeding remote control switch, so as to cause the movements of each succeeding switch to be similar to the movements of the preceding switch, means for alternately energizing the control circuits of the first remote control switch, each succeeding remote controlled switch being controlled through the independent work

circuit of the preceding switch, and means for locally breaking the energized control switches of each remote control switch and locally closing the other on each of the movements of said remote control switches, said control circuits of succeeding switches being connected to and disconnected from said work circuits respectively by the next preceding switch, the closing control circuit when energized being in multiple with the translating device in the work circuit of the preceding switch.

10. In a multiple arc system of distribution the combination of a plurality of independent work circuits arranged in multiple arc relatively to one another, a plurality of remote controlled switches arranged in succession, each independent work circuit being controlled by one of said switches, and each succeeding switch being controlled through a preceding switch, the control of any switch by the next preceding switch being independent of any other switch.

DANIEL SALAZAR M.
